CLAIM

We claim the ornamental design for an LED light panel, as shown and described.

DESCRIPTION

FIG. 1 is a front elevation view of an embodiment of an LED light panel showing the new design;

FIG. 2 is a front perspective view thereof;

FIG. 3 is a left side elevation view thereof;

FIG. 4 is a right side elevation view thereof;

FIG. 5 is a top plan view thereof;

FIG. 6 is a bottom plan view thereof; and

FIG. 7 is a rear elevation view thereof.

FIG. 8 is a front elevation view of another embodiment of an LED light panel showing the new design;

FIG. 9 is a front perspective view thereof;

FIG. 10 is a left side elevation view thereof;

FIG. 11 is a right side elevation view thereof;

FIG. 12 is a top plan view thereof;

FIG. 13 is a bottom plan view thereof; and

FIG. 14 is a rear elevation view thereof.

FIG. 15 is a front elevation view of yet another embodiment of an LED light panel showing the new design;

FIG. 16 is a front perspective view thereof;

FIG. 17 is a left side elevation view thereof;

FIG. 18 is a right side elevation view thereof;

FIG. 19 is a top plan view thereof;

FIG. 20 is a bottom plan view thereof; and,

FIG. 21 is a rear elevation view thereof.

The broken lines illustrate features of the LED light panel that form no part of the claimed design. The oblique shading lines visible in the front views denote transparency, which is part of the claimed design.
